APPARATUS FOR GUNFIRE CONTROL

Raymond E. Crooke, New York, N. Y., assignor
to Ford Instrument Company, Inc., Long Island
City, N. Y., a corporation of New York

Application September 22, 1933, Serial No. 690,540

23 Claims. (Cl. 89—41)

1

This invention relates to a method of and apparatus for controlling the firing of ordnance and more particularly to the determination and application to the ordnance of certain correctional factors required for accurately aiming it.

The invention is particularly adapted for use in systems in which guns or the like are controlled from an instrument known comprehensively as a director which measures the present position of the target in train and elevation and with the application of other quantities, such as range, speed of the target and the like, computes the predicted position of the target in train and elevation at the end of the time of flight of the projectiles. The predicted position of the target is then corrected for ballistics, such as the curvature of the trajectory of the projectiles, drift, and wind effects, thus giving the train and elevation of the gun (hereinafter referred to as uncorrected gun train and uncorrected gun elevation) as if the gun were located at the director.

When the horizontal distance between the director and a gun, usually called the base line, is appreciable it is necessary to add a horizontal parallax correction to the uncorrected gun train. In the case of ordnance being used against aerial targets it is necessary in addition to the parallax correction in train to apply a parallax correction in elevation due to the horizontal base line, as the line between the director and the target and the line between the gun and the target do not both lie in a horizontal plane, as they do in the case of surface targets.

If a director and a plurality of individual guns are located substantially on a straight line but with the guns at different distances from their controlling director, as for example, on ship-board, the parallax corrections required for the guns will vary in amount in accordance with the different lengths of the base lines. This means that each gun must have an individual parallax correction applied thereto which differs from the parallax corrections required for the remaining guns.

Heretofore two systems for applying the parallax corrections required at the different guns under the conditions explained above have been employed. In one of these systems the individual parallax corrections are determined at the guns by computing instruments associated with the guns and having co-acting elements displaceable in accordance with the factors on which the parallax corrections depend, the element which represents the base line being designed in

2

accordance with the particular value of the base line for its gun or being so constructed that it may be set in accordance with the required value of the base line for any particular gun in order that the computing instruments may be interchanged if necessary. The parallax corrections thus determined are introduced into the indicators at the guns by suitable mechanism for this purpose. The chief disadvantages of systems of this character arise from the fact that as many parallax computing instruments are necessary as there are guns, which increases the complexity and expense of the equipment required at each gun.

In the other system, there is provided for each gun a single transmitter or a pair of coarse and fine transmitters for sending, from the director to the gun, indications of the train required to be given to the gun. A similar set of transmitters is provided for sending to the gun indications of the required elevation. Means are provided by which the operation of each transmitter is modified in accordance with the base line of the gun controlled by the transmitter. In this system there must be as many sets of train and elevation transmitters as there are guns to be controlled from the director. The complexity and expense of installations of this character constitute one of their chief disadvantages which are enhanced when pairs of coarse and fine transmitters are employed, as is usually the case in present-day fire control equipment.

It is accordingly an object of the present invention to overcome the disadvantages of prior systems for applying a parallax correction to a plurality of guns, for both surface and aerial targets. In general the method consists in determining, with respect to a main reference point, such as a director, the value of the parallax correction for a secondary reference point, which may be one of the guns, and transmitting the correction to the guns, where before being applied it is modified at each gun in accordance with the ratio of the base line of the particular gun to the base line of the secondary reference point for which the parallax correction has been determined. For convenience, the base line and the parallax corrections for the above mentioned secondary reference point will be referred to as the unit base line and the unit parallax corrections, respectively.

One form of apparatus which may be employed for practicing the invention consists of an instrument for computing the parallax correction, with respect to a main reference point, for a secondary

reference point and which is provided with means for transmitting the parallax correction to the gun. At each gun devices are provided for modifying the parallax correction in accordance with the ratio of the base line of the particular gun to the base line of the secondary reference point for which the parallax correction has been computed. The guns are also provided with suitable receivers for receiving the indications of uncorrected gun train and elevation transmitted from the director and with means for combining with these indications the modified parallax corrections, in order that the guns may be correctly trained and pointed.

The particular nature of the invention, as well as other objects and advantages thereof, will appear most clearly from a description of a particular embodiment as illustrated in the simplified drawing in which D indicates in general a director including a computor C for determining the unit parallax corrections to be transmitted to gun units G_A and G_B.

Preliminary to describing the apparatus in detail, it will be explained that the parallax computer is intended to solve the following equations which in practice give sufficiently accurate results for the purpose for which the invention is intended to be used, it being understood that in order to simplify consideration of the problem involved herein, no account is taken of the angular movements of the ship with respect to the surface of the sea. In other words, the ship is assumed to be on an even keel.

$$(1) \quad P_T = K_1 \times \frac{\sin T_2}{R_2} \times \sec E_2$$

$$(2) \quad P_E = K_2 \times \frac{\cos T_2}{R_2} \times \sin E_2$$

In these equations

P_T represents the parallax correction in train due to a horizontal base line which may be regarded as unity. Therefore the base line does not appear as a term of the equation;

P_E represents the parallax correction in elevation due to the same horizontal base line;

E₂ represents the predicted elevated of the target;

T₂ represents the predicted train of the target;

R₂ represents the predicted range of the target;

K₁, K₂ are constants due to trigonometric approximations used in the equations.

Assuming that the parallax correction has been determined for a horizontal base line A, the relation between the parallax correction in train due to a horizontal base line B, designated P_{TB}, and that due to the horizontal base line A, designated P_{TA}, may be expressed as follows:

$$(3) \quad \frac{P_{TB}}{P_{TA}} = \frac{\text{Base line } B}{\text{Base line } A}$$

Similarly the relation between the parallax correction in elevation due to the horizontal base line B, designated P_{EB}, and that due to the horizontal base line A, designated P_{EA}, may be expressed as follows:

$$(4) \quad \frac{P_{EB}}{P_{EA}} = \frac{\text{Base line } B}{\text{Base line } A}$$

Referring to the drawing the director D includes a pedestal 1 fixed to the ship and provided with an annular rack 2 within which a table 3 is rotatably mounted upon the pedestal. The table is provided with a standard 4 carrying a shaft 5 provided with handwheels 6 to be used by the trainer of the director. Attached to the shaft 5

is a bevel gear 7 engaging a bevel gear 8 on the end of a shaft 9 supported in the standard 4 and carrying at its lower end a pinion 10 engaging the rack 2. A compound gear 11 has a bevel gear meshing with bevel gear 7 and a spur gear meshing with a gear attached to the side 12' of a differential 12. The other side 12'' of the differential is provided with a gear meshing with a gear 13 attached to the end of a crank 14 by which correctional factors, other than parallax, may be introduced into the values of train transmitted from the director to the gun. In practice the crank will be provided with an indicator to guide the operator in properly adjusting the crank for particular values of the factors.

The center 12''' of the differential is connected through a train of gears 15 to a shaft 16 which is attached to the rotor of a coarse transmitter 17. The shaft 16 is connected by a train of gears 18 to a shaft 19 to which is attached the rotor of a fine transmitter 20. These transmitters send to the guns over conductors 21, which for simplicity are shown as a single line, indications of the corrected train required to be given to the guns for properly aiming the latter, excepting for the parallax correction, as will be hereinafter described.

Attached to the table 3 is a standard 22 carrying a shaft 23 to which are attached handwheels 24 to be used by the pointer of the director. Attached to the shaft 23 is a bevel gear 25 meshing with the bevel gear of a compound gear 26 the spur gear of which meshes with a gear attached 35 to the side 27' of a differential 27. The other side, 27'', of the differential is provided with a gear which meshes with a gear 28 attached to the end of a crank 29 by which correctional factors, other than parallax, may be introduced 40 into the values of elevation transmitted from the director to the gun. As is the case of crank 14, this crank will in practice be provided with a suitable indicator.

The center 27''' of the differential is connected through a train of gears 30 to a shaft 31 to which is attached the rotor of a coarse transmitter 32. The shaft 31 is connected by a train of gears 33 to a shaft 34 to which is attached the rotor of a fine transmitter 35. Suitable conductors 36, shown conventionally as a single line, lead from the coarse and fine transmitters to transmit to the guns indications of the corrected elevation required to be given to the guns for properly aiming the latter excepting for the parallax correction, as will be herein-after described.

From the spur gear of the compound gear 26 a train of gears 37 drives a shaft 38 which, through a pair of gears 39, shaft 40 and pair of gears 41, drives a worm 42 co-acting with a gear sector 43 on a shaft 44 rotatably mounted in a standard 45 which will be understood to be attached to the table 3 of the director. The shaft 44 carries at one end a telescope 46 for use by the pointer 45 and at the other end a corresponding telescope 47 for use by the trainer, in accordance with the usual arrangement of directors of the two-telescope type.

In addition to the mechanism already described as being mounted on the table 3, the several elements of the parallax computor C about to be described, are also mounted on the table by suitable supports which for simplicity have been omitted from the drawing.

A crank 48 is adapted to be turned in accord-

ance with values of the predicted train of the target as obtained from a suitable predicting apparatus for this purpose, it being understood that in practice an indicator will be associated with the crank in order that the latter may be operated in accordance with values of predicted train. The crank 48 carries a bevel gear 49 engaging a corresponding gear on the side 50' of the differential 50. The crank is also connected through a gear train 51 to a disc 52 provided with a radial slot through which passes a pin 53 which also passes through other associated elements as will presently be described.

A crank 54 is arranged to be turned in accordance with values of predicted range as received from a suitable source of information, it being understood that a suitable indicator will in practice be associated with the crank. The crank 54 is provided with a bevel gear 55 meshing with a similar gear on the side 50" of differential 50. The center 50''' of the differential is connected by a shaft and a gear train 56 to a disc 57 provided with a cam groove, shown in broken lines, into which pin 53 extends. The pin 53 also passes through a slot in one arm of a T-shaped slide 58. A similar slide 59 also has a slotted arm through which the pin 53 extends. By virtue of the elements just described, the radial slot in the disc 52 and the cam groove in the disc 57 actuate the pin 53 when the discs are properly set, to cause movement of the slide 58 in accordance with the factor

$$\frac{\sin T_2}{R_2}$$

of Equation 1, and to cause movement of the slide 59 in accordance with the factor

$$\frac{\cos T_2}{R_2}$$

of Equation 2, it being understood that the constants K_1 and K_2 of these equations are introduced at appropriate points by suitable gear ratios as is customary in instruments of this nature.

In practice, under certain conditions, the predicted train T_2 may be constant, while the predicted range R_2 may vary. In this case the crank 48 will not be turned, so that the side 50' of the differential and the disc 52 remain stationary. The adjustment of the crank 54 in accordance with varying values of predicted range will then drive through the side 50" and center 50''' of the differential and gear train 56, the disc 51 to alter the slides 58 and 59 in accordance with changing values of R_2 for constant values of T_2 .

If, on the other hand, the predicted range R_2 remains constant, while the value of the predicted train T_2 varies, the crank 54 will be held stationary. Under these conditions the side 50" of the differential will also remain stationary and the movement imparted to the crank 48 will drive the disc 52 and also through the center 50''' of the differential and gear train 56, the disc 51 will be driven in unison with the disc 52 to alter the positions of slides 58 and 59 in accordance with the effect upon the factors represented by these slides of the changing values of T_2 for constant values of R_2 .

A crank 60 is adapted to be turned in accordance with the values of predicted elevation E_2 , it being likewise understood that a suitable indicator will be associated with the crank. The crank drives through a train of bevel gears 61, a shaft 62 provided at its upper end with a pinion

63 co-acting with a disc 64 provided with a cam groove formed in accordance with values of the sine of the predicted elevation E_2 . Fitted within the cam groove is a pin 65 attached to one end of a rectangular slide 66 having a slotted arm through which passes a pin 67. This pin also passes through a slotted link 68 one end of which is slidably pivoted about a fixed pin 69. The other end of the link is pivotally attached to a slide 70 provided with a rack engaging a gear on the end of a shaft 71, which carries at its other end a similar gear engaging a rack on the slide 59. The pin 67 also passes through the slotted arm of a T-shaped slide 72 which is provided with a rack for driving through a gear train 73, a shaft 74 to which is attached the rotor of a transmitter 75 connected through conductors 76, shown for simplicity as a single line, to receivers at the guns as will hereinafter be described.

Since the slide 70 is driven directly from the slide 59 which moves in accordance with values of the factor

$$\frac{\cos T_2}{R_2}$$

and this movement is imparted to the link 68 and since the slide 66 is moved in accordance with values of the factor $\sin E_2$, the movement imparted to the pin 67 and hence to the slide 72, will be in accordance with the product of these factors. By introducing the constant K_2 in the gear ratios, as previously explained, the movement imparted to shaft 74 and the rotor of the transmitter 75 will be in accordance with Equation 2 for the parallax correction in elevation.

The shaft 62 carries at its lower end a pinion 77 coacting with a disc 78 provided with a cam groove formed in accordance with values of the secant of the predicted elevation E_2 . Fitting in the cam groove of the disc 78 is a pin 79 attached to a rectangular slide 80 having a slotted arm through which a pin 81 passes. The pin also passes through a slotted link 82 one end of which is slidably pivoted about a fixed pin 83. The other end of the link is pivotally connected to a slide 84 which is provided with a rack co-acting with a gear on a shaft 85 which carries a second gear meshing with a rack on the slide 58. The pin 81 also extends through the slotted arm of a T-shaped slide 86 provided with a rack which through a gear train 87, drives the rotor shaft 88 of a transmitter 89 which is connected by suitable conductors, shown conventionally as a single line 90, to receivers at the guns, as will hereinafter be described.

By virtue of the devices just described, the slide 84 and accordingly the link 82, receives from the slide 58 a movement in accordance with the factor

$$\frac{\sin T_2}{R_2}$$

and the slide 80 receives through pin 79 a movement in accordance with $\sec E_2$. By the introduction of the constant K_1 in the gear ratios of the instrument, the slide 86 receives a movement in accordance with Equation 1 for the parallax correction in train, the value of which is sent by the transmitter 89 and conductor 90 to the guns.

Two gun units G_A and G_B are shown, these units being located at distances from the vertical center line of the director indicated by the legends "Base line A" and "Base line B" respectively. For convenience, and since the guns and

most of the devices associated with them are identical in the two units, corresponding elements in the units will be designated by the same reference characters, an exception being made in the case of those elements which differ from each other in the two units.

Each unit includes a gun 91, mounted by trunnions in standards on a turntable 92 in the usual manner. The gun is adapted to be trained by handwheels 93 on a shaft 94 which, through bevel gears 95, drives a shaft 96 mounted in a standard on the turntable and provided with a pinion 97 meshing with a fixed annular rack 98 surrounding the turntable of the gun. The gun is provided with an elevating rack 98 engaging a pinion on a shaft 99 which, through a gear train 100, is connected to a shaft 101 carrying handwheels 102 by which the gun may be elevated in the usual manner. The elements above described are shown in more or less diagrammatic manner, it being understood that they as well as the elements about to be described will be arranged to move with the gun as it is trained.

The conductors from the coarse and fine train transmitters 17 and 20 respectively, shown collectively as a single line 21, lead to the rotors of coarse and fine receivers 103 and 104 respectively, at the guns, these receivers being shown as of the zero-reading type with rotatable stators and each rotor shaft carrying a dial 105 provided with an index adapted to be read against a fixed index 106. Driven from the shaft 99 of the training gear of the gun is a shaft 107 carrying a bevel gear 108 which meshes with a corresponding gear formed on the side 109' of a differential 109. The center 109''' of the differential is connected by a shaft 110, bevel gears 111, shaft 112 and gear train 113 to the rotatable stator 114 of the coarse receiver 103. The shaft 110 is also connected by a gear train 115 to the rotatable stator 116 of the fine receiver 104. It will be understood that the ratio of the speeds at which the coarse and fine stators are driven from the shaft 110 corresponds to the ratio of the speeds between the rotors of the coarse and fine transmitters 17 and 20 respectively, as is the usual practice in transmission systems of the character illustrated herein.

The conductors from the Pt transmitter 89, indicated collectively by the single line 90, lead to the rotor of a zero-reading receiver 117, the rotor of which carries a dial 118 having an index adapted to be read against a fixed index 119. The rotatable stator of the receiver 117 is adapted to be turned by a crank 120 and a pinion 121. In unit Ga the crank 120 also drives through a pair of bevel gears 122 a spur gear 123 which engages another spur gear 124 on a shaft 125 which is connected by a bevel gear 126 to the side 109'' of the differential 109.

At this point it may be explained that the gun unit Ga is the one for which the parallax corrections in train and elevation generated in the parallax computor of the director are suitable for application without modification. The parallax correction in train applied at this gun may, therefore, be regarded as one of the unit parallax corrections referred to in the introduction. The fact that this unit parallax correction is applied to the gun unit Ga without modification is indicated by the gears 123 and 124 being shown of the same diameter, whereas in the gun unit Gb the corresponding gears 123' and 124' are shown in a 1:2 ratio since the base line B is one-half the length of the base line A.

The conductors indicated by 36 leading from

the coarse and fine elevation transmitters 32 and 35, respectively, are connected to the rotors of zero-reading coarse and fine receivers 127 and 128, respectively, each receiver having a rotatable stator and its rotor being provided with a dial 129 having an index adapted to be read against a fixed index 130. The shaft 99 of the gun elevating mechanism is connected by a bevel gear 131 to a corresponding gear formed on the side 132' of a differential 132. The center 132''' of the differential is connected by shaft 133 and pinion 134 to the rotatable stator of the coarse receiver 127. This shaft is also connected through gear train 135 to shaft 136 and gear train 137 to the rotatable stator of the fine receiver 128, the speed ratio between the stators of the coarse and fine receivers being the same as the speed ratio between the rotors of the coarse and fine transmitters 32 and 35, respectively.

The conductors indicated by 76 leading from the Pe transmitter 75 go to a zero-reading receiver 138, the rotor of which is provided with a dial 139 having an index reading against a fixed index 140. The stator of this transmitter is adapted to be turned by a crank 141 and pinion 142. In unit Ga the crank 141 also drives through a pair of bevel gears 143, shaft 144, gear 145, gear 146 and bevel gear 147 a corresponding bevel gear formed on the side 132'' of the differential 132.

As explained above in connection with the parallax correction in train, the parallax correction in elevation which is applied to the gun unit Ga may be regarded as the unit parallax correction since it requires no modification. This is indicated by the fact that the gears 145 and 146 of this unit are of the same diameter, while the corresponding gears 145' and 146' of gun unit Gb have a 1:2 ratio on account of the similar ratio of the base line B to the base line A.

In the operation of the apparatus described above, the trainer keeps his telescope 47 on the target by suitable manipulation of his handwheels 6 which through shaft 5, gears 7 and 8, shaft 9 and pinion 10 will cause the table 3 to be turned within the fixed annular rack 2. At the same time the handwheels will, through gear 7 and compound gear 11, drive the side 12' of differential 12. The side 12'' will be driven in accordance with the correctional factors which are continuously or from time to time introduced by manipulation of crank 14. The movements imparted to the sides of the differential are combined at its center 12''' and from it imparted to the rotors of the coarse and fine transmitters 17 and 20, respectively.

The movements of these rotors will be reproduced in the coarse and fine receivers 103 and 104, respectively, at the guns to correspondingly displace the indexes on the dials 105 with respect to the fixed indexes 106. The trainers at the guns will turn their handwheels 93 which, through shafts 94, bevel gears 95, shafts 96 and pinions 97, will rotate the turntables 92 on which the guns are mounted. At the same time, through shafts 107 and bevel gears 108, the sides 109' of the differentials 109, will be correspondingly rotated. Assuming for the time being that the cranks 120 are stationary, the sides 109'' of the differentials will be stationary so that the movements imparted by the handwheels will be transmitted from the centers 109''' of the differentials through shafts 110, gears 111, shafts 112 and gear trains 113 and 115 to the stators 114 and 116 of the train receivers 103 and 104, respectively. The

trainers will rotate their handwheels until the indexes on the dials of the receivers have been restored to coincidence with the fixed indexes 106 to indicate to the trainers that the guns have been trained in accordance with the information transmitted from the director, in a manner well known in transmission systems of the type employed herein.

Simultaneously with the operation of the training mechanism described above, the pointer at the director will, if the system is being operated for continuous aim, manipulate his handwheels 24 to maintain his telescope 46 on the target in elevation, through shaft 23, gear 25, compound gear 26, gear train 37, shaft 38, gears 39, shaft 40, gears 41, worm 42 and gear sector 43 attached to the shaft 44 on which the telescope is mounted. At the same time the compound gear 26 will drive the side 27' of differential 27 and corrections in elevation will be applied by manipulation of crank 29 to correspondingly position the side 27" of the differential by gear 28 on the crank. The movements imparted to the sides of the differential will be combined at its center 27''' and through gear train 30 and shaft 31 the rotor of the coarse transmitter 32 will be accordingly turned and through gear train 33 and shaft 34 the rotor of fine transmitter 35 will be turned. The resulting movements of these rotors will be transmitted over conductors 36 to the coarse and fine receivers 127 and 128, respectively, at the guns to cause corresponding displacements of the indexes on dials 129 with respect to the fixed indexes 130.

The pointers at the guns will manipulate their handwheels 102 to elevate or depress the guns through shafts 101, gear trains 100, shafts 99 and elevating racks 98. Simultaneously the shafts 99 will, through gears 131, drive the sides 132' of differentials 132. Assuming that the cranks 141 are stationary, the other sides 132" of the differentials will be stationary so that the movements of the sides 132' will be imparted to the centers 132''' and to shafts 133 and pinions 134 to correspondingly turn the stators of the coarse receivers 127. At the same time the stators of the fine receivers 128 will be driven from the shafts 133 through gear trains 135, shafts 136 and gear trains 137. The pointers will continue to rotate their handwheels until the indexes on the dials 129 have been restored to coincidence with the fixed indexes 130 indicating that the guns have been elevated in accordance with the data sent from the director.

While the trainer and pointer of the director are operating their chains of mechanism to enable the trainers and pointers at the guns to properly aim the guns in accordance with the required train and elevation of the target, corrected for factors other than parallax, other operators will be introducing inputs of predicted elevation E_2 , predicted train T_2 and predicted range R_2 by manipulation of cranks 60, 48 and 54, respectively, to actuate the associated mechanisms of the parallax computor C as previously explained. The final result of these operations will be to impart to the rotor of the transmitter 89 a movement in accordance with the required parallax correction in train which will be transmitted over conductors 90 to the parallax receivers 117 at the guns to correspondingly displace their rotors and the indexes on their dials 118 with respect to the fixed indexes 119. At the same time the cranks 120 will be turned by operators who observe the dials 118 and restore the indexes

thereon to coincidence with the fixed indexes 119 by rotation of the stators of the receivers by the pinions 121 on the cranks 120.

The movement imparted to the crank 120 of gun unit GA will through gears 122, 123, 124, shaft 125 and gear 126 correspondingly turn the side 109' of differential 109, to impart to the center 109''' of the differential a movement corresponding to the required parallax correction in train in addition to the movement imparted to it from the side 109' of the differential as described above. The additional movement of the center of the differential due to the parallax correction applied to it will superimpose upon the movement originally imparted to the stators of the train receivers 103 and 104 an additional displacement which must be taken into account by the trainer as he turns his gun to place the indexes on the dials 105 in coincidence with the fixed indexes 106. When this has been done the required parallax correction will have been applied to gun 91 of unit GA, which, as explained above, is the unit for which the parallax correction generated by the parallax computor has unit value.

Since the parallax correction generated at the director is transmitted without modification to the parallax receiver 117 at the gun unit GB to correspondingly displace its dial 118, it is necessary to modify this correction at this unit before it is applied to the gun. As in the case of the unit GA, the crank 120 of the unit GB will be manipulated to turn its pinion 121 and the stator of the receiver until the index on the dial is brought into coincidence with the fixed index 119, but the movement imparted to the side 109''' of the differential 109 of this unit will be reduced by the ratio of gears 123' and 124', in proportion to the relation between the base line B and base line A, as previously described. The subsequent operations performed by the gun trainer of unit GB will be like those described in connection with unit GA so that ultimately the required parallax correction in train will be imparted to the gun 91 of unit GB.

As previously described, the rotor of the transmitter 75 at the director will be turned in accordance with the required parallax correction in elevation which will be reproduced in the rotors and dials 139 of the receivers 138 of the guns. The indexes on the dials will be restored to coincidence with the fixed indexes 140 by rotating the stators of the receivers by manipulation of the cranks 141 and pinions 142. In the case of gun unit GA the movement of crank 141 will cause through bevel gears 143, shaft 144, gears 145, 146 and 147, a corresponding movement of the side 132''' of differential 132. The movement transmitted from the crank 141 to the side 132''' will be in 1:1 ratio as described in connection with the parallax correction in train and for the same reason.

In gun unit GB, on the other hand, the transmission from the crank 141 to the side 132''' of the differential will be in a 1:2 ratio on account of the lesser base line of this unit, this ratio being obtained by suitable proportioning of the gears 145' and 146' of this unit.

In both units, however, the result of the application of the parallax correction in elevation will be to cause through the movements of the centers 132''' of the differentials 132, shafts 133 and the gears by which they are connected to the stators of the elevation receivers 127, 128, an additional displacement of the rotors and dials of these receivers, these additional displacements

being compensated for by the pointers at the guns imparting additional movements to the guns by operation of their handwheels in a manner similar to that described in connection with the application of the parallax correction in train.

Since the device for modifying the parallax corrections received at the different gun units include gear trains having different ratios, the units may be interchangeably arranged with respect to the director by the selection of suitable gear ratios in accordance with the base lines of the units.

While a preferred embodiment of the invention has been shown and described, it will be understood that the invention may be embodied in other forms and that various changes may be made in structural details without departing from its principles as defined in the appended claims.

I claim:

1. In a fire control system, the combination of a plurality of guns, means for determining values of a correctional factor for one of the guns comprising elements adjustable in accordance with the future position of a movable target, means for transmitting the values of the factor to that gun and to the remaining guns, and means at each of said remaining guns for converting the values transmitted thereto to the particular values of the factor required for that gun.

2. In a fire control system, the combination of a plurality of guns, means operable in accordance with the anticipated future position of a target for determining values of a correctional factor for adjusting the aim of one of the guns, means for transmitting the values of the factor to that gun and to the remaining guns, and means at each of said remaining guns for converting the values transmitted thereto to the particular values of the factor required for that gun, each of said last named means including co-acting elements having a motion transmitting ratio depending upon the particular conversion which the means effects.

3. In a fire control system, the combination of a plurality of guns, means operable in part in accordance with predicted train and elevation of a movable target for determining values of correctional factors for one of the guns, means for transmitting the values of the factors to that gun and to the remaining guns, means at each of the guns for receiving the transmitted values for directing the aim of the guns, and means associated with the receiving means at each of the remaining guns for converting the values of the factors received thereat to the values required for that gun.

4. In a fire control system, the combination of a plurality of guns, means operable in accordance with predicted train, elevation and range of a movable target for determining values of correctional factors for one of the guns, means for transmitting the values of the factors to that gun and to the remaining guns, means at each of the guns for receiving the transmitted values, means associated with the receiving means at each of the remaining guns for converting the values of the factors received thereat to the values required for that gun and means associated with the last named means for directing the aim of the gun.

5. In a fire control system, the combination of a plurality of guns requiring different values of a correctional factor for their aiming, means for determining an arbitrary value of the factor, a transmitting device common to all the guns and

operable by the determining means for transmitting the arbitrary value of the factor to the guns, means at each of the guns for receiving the transmitted value for directing the aim of the gun, and means associated with each receiving means operable in accordance with the arbitrary value of the factor received thereat including means for converting said arbitrary value to the particular value required for that gun.

6. In a fire control system, the combination of a plurality of guns requiring different values of a correctional factor for their aiming at an anticipated future position of a target, means operable in accordance with quantities dependent upon the future position of the target for determining the value of the factor for one of the guns, means for transmitting the determined value to that gun and to the remaining guns, means at each of the guns for receiving the transmitted value and means associated with the receiving means at each of the remaining guns for converting the value of the factor received thereat to the value required for that gun.

7. In a fire control system, the combination of a plurality of guns requiring different values of a correctional factor for their aiming, means for determining an arbitrary value of the factor, a transmitting device common to all the guns and operable by the determining means for transmitting the arbitrary value of the factor to the guns and means at each of the guns operable in accordance with the arbitrary value of the factor received thereat and including means for converting said arbitrary value to the particular value required for that gun.

8. In a fire control system, the combination of a plurality of guns requiring different values of parallax correction for their aiming, means for determining an arbitrary value of the parallax correction, a transmitting device common to all the guns and operable by the determining means for transmitting the arbitrary value of the parallax correction to the guns and means at each of the guns operable in accordance with the arbitrary value of the parallax correction received thereat and including means for converting said arbitrary value to the particular value required for that gun.

9. In a fire control system, the combination of a plurality of guns each requiring different values of correctional factors affecting the aiming thereof, means for determining values of the correctional factors for a particular gun, a transmitting device common to all the guns and operable by the determining means for transmitting the values of the factors to the particular gun and the remaining guns, means at the particular gun for applying thereto the determined values of the correctional factors and means at each of the remaining guns for applying thereto the determined values of the correctional factors modified in accordance with the particular values required for the gun.

10. In a fire control system, the combination of a plurality of guns located at different distances from a reference point, mechanism for determining the parallax correction with respect to the reference point for a particular gun, means for transmitting the parallax correction to the particular gun and the remaining guns, means at the particular gun for applying thereto the parallax correction and means at each of the remaining guns for applying thereto the parallax correction modified in accordance with the distance of the gun from the reference point.

11. In a fire control system, the combination of a plurality of guns located at different distances from a reference point, mechanism for determining the parallax correction with respect to the reference point for a particular gun, means for transmitting the parallax correction to the particular gun and to the remaining guns, and means for modifying the parallax correction as received at said remaining guns in accordance with the different distances of the guns from the reference point.

12. In a fire control system, the combination of a directing device, a plurality of guns located at different distances from the device, means at the device for determining the parallax correction for a particular gun, means at the device for transmitting the parallax correction to the particular gun and to the remaining guns, and means at each of said remaining guns for modifying the parallax correction received thereat in accordance with the distance of the gun from the directing device.

13. In a fire control system, the combination of a plurality of guns requiring for their aiming a common value of a main factor and different individual values of a correctional factor, means for transmitting the common value to all of the guns, means at each gun for receiving the transmitted values of the common factor, means for determining the value of the correctional factor for one of the guns, means for transmitting the determined value of the correctional factor to that gun and to the remaining guns, means at each gun for receiving the transmitted value of the correctional factor, means associated with both receiving means at each remaining gun for converting the value of the correctional factor received thereat to the value required for that gun, and means under the control of both receiving means and the converting means at each gun for directing the aim of the gun.

14. In a fire control system, the combination of a directing device, a plurality of guns requiring for their aiming a common value of a main factor and different individual values of a correctional factor, means under the control of the directing device for transmitting the common value to all of the guns, means at each gun for receiving the transmitted value of the common factor, means for determining the value of the correctional factor for one of the guns, means for transmitting the determined value of the correctional factor to that gun and to the remaining guns, means at each gun for receiving the transmitted value of the correctional factor and means associated with both receiving means at each remaining gun for converting the value of the correctional factor received thereat to the value required for that gun.

15. In a fire control system, the combination of a plurality of guns, means for determining values of a correctional factor for a reference point, means for transmitting the values of the factor to each of the guns and means at each of the guns for converting the values of the factor transmitted thereto to the particular values of the factor required for that gun in accordance with its relation to the reference point.

16. In a fire control system, the combination of a plurality of guns located at different distances from a main reference point, means for determining values of a correctional factor for a secondary reference point, means for transmitting the values of the factor to each of the guns and means at each of the guns for converting

the values of the correctional factor transmitted thereto to the particular values of the factor required for that gun in accordance with its relation to the secondary reference point.

17. In a fire control system, the combination of a directing device, a plurality of guns requiring for their aiming common main values of train and different individual values of a correctional factor of train, means under the control of the directing device for transmitting the common main values to all of the guns, means at each gun for receiving the transmitted common main values, means for determining arbitrary values of the correctional factor of train, a transmitting device common to all the guns and operable by the determining means for transmitting the determined arbitrary values of the correctional factor to each of the guns, means at each gun for receiving the transmitted arbitrary values of the correctional factor, means associated with each gun for converting the arbitrary values of the correctional factor received at the gun to the value required for that gun, and means at each gun under the control of both said receiving means at the gun for directing the aim of the gun.

18. In a fire control system, the combination of a directing device, a plurality of guns requiring for their aiming common main values of elevation and different individual values of a correctional factor of elevation, means under the control of the directing device for transmitting the common main values to all of the guns, means at each gun for receiving the transmitted common main values, means for determining arbitrary values of the correctional factor of elevation, a transmitting device common to all the guns and operable by the determining means for transmitting the determined arbitrary values of the correctional factor to each of the guns, means at each gun for receiving the transmitted arbitrary values of the correctional factor received at the gun to the value required for that gun, and means at each gun under the control of both said receiving means at the gun for directing the aim of the gun.

19. In a fire control system, the combination of a directing device, a plurality of guns requiring for their aiming common main values of train and elevation and different individual values of a correctional factor of train and elevation, means under the control of the directing device for transmitting the common main values to all of the guns, means at each gun for receiving the transmitted common main values, means for determining arbitrary values of the correctional factor of train and elevation, a transmitting device common to all the guns and operable by the determining means for transmitting the determined arbitrary values of the correctional factor to each of the guns, means at each gun for receiving the transmitted arbitrary values of the correctional factor received at the gun to the value required for that gun, and means at each gun under the control of both said receiving means at the gun for directing the aim of the gun.

20. In a fire control system, the combination of a directing device, a plurality of guns located at different distances from the device, means at the device for determining values of a correc-

tional factor for a reference point, means at the device for transmitting the values of the factor to each of the guns and means at each of the guns for modifying the values of the correctional factors received thereat in accordance with the relation of the gun to the reference point.

21. In a fire control system, the combination of a plurality of guns, means for determining a value of a correctional factor required for the aiming of one of the guns, a transmitting device common to all the guns and operable by the determining means for transmitting to said one of the guns and to the remaining guns the determined value of the correctional factor, means at each of the guns for receiving the transmitted value of the correctional factor and means associated with the receiving means at each of the remaining guns for converting the received value of the correctional factor to the particular value of the factor required for that gun.

22. In a fire control system, the combination of a plurality of guns each requiring for its aiming a value of a correctional factor differing from the values required for the other guns, means for determining an arbitrary value of the factor, a transmitting device common to all the guns and operable by the determining means for transmitting to the guns the arbitrary value of the factor, means at the guns jointly responsive to

the transmitting device for receiving the arbitrary value of the factor and means associated with the receiving means at each of the guns for converting the arbitrary value of the factor to the particular value of the factor required for that gun.

23. The combination with a plurality of guns, of means for determining a correction factor for laying one of said guns, means for transmitting said factor to each gun of said plurality of guns, and mechanical means including gear trains having different ratios associated with each gun to apply said factor to the respective guns, the said ratios being proportionate to the distance of the respective gun from a reference point.

RAYMOND E. CROOKE.
